UNITED STATES PATENT OFFICE

PERCE R. GALT, OF MERCHANTVILLE, NEW JERSEY

RAZOR

Application filed April 16, 1932. Serial No. 605,585.

This invention relates to a razor and more particularly to a razor of the safety type having a double-edged blade in which a movement is imparted to the blade to facilitate shaving.

In the ordinary safety razor the blade is moved during a cutting operation at substantially a right angle to the cutting edge. The cutting effect may be considerably enhanced by moving the razor at an angle to the cutting edge so that a slicing action is obtained. It is the broad object of the present invention to produce a movement of the blade in the direction of its cutting edge so as to effect automatically this slicing action.

The present application relates primarily to a construction forming an improvement over that disclosed in my application Serial No. 573,039 filed November 5, 1931, of which the present application is in part a continuation.

Detailed objects of the invention relating particularly to features of construction will be apparent from the following description read in conjunction with the accompanying drawing in which:

Fig. 1 is an elevation of a razor embodying the preferred form of the invention;

Fig. 2 is a section taken longitudinally through the blade;

Fig. 3 is an inverted plan view of the same with the cover removed and certain parts broken away and in section;

Fig. 4 is an end elevation of the razor; and

Fig. 5 is a section taken substantially on the plane indicated by 5—5 in Fig. 2.

The handle of the improved razor is indicated at 2, this handle being internally threaded to engage the upstanding threaded post 4 secured to the holder 6. This holder is preferably of a light metal such as an aluminum casting and is formed to provide suitable mounting for the various parts as will be more particularly apparent hereafter.

A suitable slot in the holder 6 provides a mounting for a slide 8 which is arranged to have a limited oscillatory movement, being held in position on the holder by the head of a screw 12, the shank of which passes through an elongated slot 10 in the slide.

At one end the slide carries an inwardly directed pin 14 engaged within an opening in a transverse lever 16 the ends of which engage within suitably shaped grooves in cams 18 carried by rotary members 20 which are adapted to engage the face of the user. These rotary members are preferably provided with knurled surfaces so that a frictional engagement with the face is obtained. As either of the rotary members revolves the cam carried thereby by engagement with the corresponding end of the lever 16 causes such lever to fulcrum about its engagement with the other cam as a pivot and thus produces a movement of the pin 14 and the slide and blade secured thereto. By reason of this construction it will be obvious that either of the rollers may take control of the oscillatory movements of the slide without interfering with the other. That is, the oscillatory movements take place without the necessity of having rotary movements of both of the members 20.

To secure the blade 30 to the slide 8 there are provided two members 22, each of which is provided with a head 24 partially circular for reception within the usual circular portion of a blade opening and partially elongated so that while the elongated portion will pass through the elongated slot in the blade so in one position it may be turned through a right angle to clamp the blade when the assembly is completed. The members 22 are provided with shanks pivoted in the slide 8 and carrying at their inner ends heads 26 between which and the inner surface of slide 8 are spring washers 28 which tend to clamp the heads 24 against the outersurface of the slide. By reason of this arrangement and the fact that the slide is provided with a plain outer face, the blade is held in flat condition rather than in the arcuate condition usually assumed in razors of conventional type. It is found that this arrangement of the blade is particularly advantageous in the razor herein described.

A cover 32 is provided at one side with ears whereby it is pivoted to the holder in position covering the blade except at the blade's cutting edges. Suitable ears 36 are

provided at the other side of the cover resiliently engaging lugs 38 to normally hold the cover in position covering the blade. When it is desired to change the blade the engagement between the ears 36 and the lugs 38 is readily broken by the application of moderate force. It is to be noted that the longitudinal edges of the cover closely approach the rotary members 20 providing restricted openings through which the cutting edges of the blade project. Inasmuch as when the razor is in use the skin extends from one of the rollers 20 across the restricted opening to the cover 32, it will be obvious that with proper dimensioning only the necessary projection of the blade will result so that while proper cutting of the hairs is permitted, danger of cutting the skin will be minimized. It will be obvious that numerous modifications may be made without departing from the spirit of the invention as defined by the following claims.

What I claim and desire to protect by Letters Patent is:

- 25 1. A razor comprising a holder adapted to mount a double-edged blade for sliding movements in the direction of its cutting edges, and means for imparting oscillatory movements of this character to the blade during shaving, said means including a slide mounted in the holder and having connection with the blade, a lever fulcrumed on the slide, rotary members arranged to engage the face, and cams carried by the rotary members and engaging the ends of the lever.
- 30 2. A razor comprising a holder adapted to mount a double-edged blade for sliding movements in the direction of its cutting edges, and means for imparting oscillatory movements of this character to the blade during shaving, said means including a slide mounted in the holder and having connection with the blade, a pin carried by the slide, a lever provided with a hole receiving said pin, rotary members arranged to engage the face, and cams carried by the rotary members and engaging the ends of the lever.
- 35 3. A razor comprising a holder adapted to mount a double-edged blade for sliding movements in the direction of its cutting edges, means for imparting oscillatory movements of this character to the blade during shaving, said means including a slide mounted in the holder and having connection with a blade, rotary members arranged to engage the face, and means whereby the rotary members produce oscillations of the slide, and a cover pivoted to the holder and slightly spaced from the rotary members to provide restricted openings thru which the cutting edges of the blade may project.

- 40 4. A razor comprising a holder adapted to mount a double-edged blade for sliding movements in the direction of its cutting edges, means for imparting oscillatory movements

of this character to the blade during shaving, said means including a slide mounted in the holder and having connection with a blade, rotary members arranged to engage the face, and means, including a lever pivoted on the slide and engaging cams carried by the rotary members, whereby the rotary members produce oscillations of the slide, and a cover pivoted to the holder and slightly spaced from the rotary members to provide restricted openings through which the cutting edges of the blade may project.

5. A razor comprising a holder adapted to mount a double-edged blade for sliding movements in the direction of its cutting edges, means for imparting oscillatory movements of this character to the blade during shaving, said means including a slide mounted in the holder and having connection with a blade, rotary members arranged to engage the face, and means whereby the rotary members produce oscillations of the slide, the means for connecting a blade to the slide including spring pressed elements engageable within slots in the blade and provided with heads engaging the blade to hold the same flatwise against the slide.

In testimony of which invention, I have hereunto set my hand, at Philadelphia, on this 4th day of April, 1932.

PERCE R. GALT.
